Primary Examiner — April Rivas(74) *Attorney, Agent, or Firm* — Edward S. Podszus**CLAIM**

The ornamental design for a surface-mountable heat sink, as shown and described.

DESCRIPTION

FIG. 1 is a top view of the design for a surface-mountable heat sink;

FIG. 2 is a front elevational view thereof, the opposite rear view being the same;

FIG. 3 is a bottom view thereof;

FIG. 4 is a side elevational view thereof, the opposite side view being the same;

FIG. 5 is a front, top perspective view thereof; and,

FIG. 6 is a bottom perspective view thereof.

The broken-line disclosure in the views is understood to represent portions of the article in which the claimed design is embodied, but which form no part of the claimed design.
